UNITED STATES PATENT OFFICE.

ISIDOR KELLNER, OF CHICAGO, ILLINOIS, ASSIGNOR TO MANHATTAN NOVELTY COMPANY, OF CHICAGO, ILLINOIS, A CORPORATION OF ILLINOIS.

RECEPTACLE FOR PHOTOGRAPHS OR THE LIKE.

SPECIFICATION forming part of Letters Patent No. 792,709, dated June 20, 1905.

Application filed April 6, 1903. Serial No. 151,271.

To all whom it may concern:

Be it known that I, ISIDOR KELLNER, a citizen of the United States of America, residing at Chicago, in the county of Cook and State 5 of Illinois, have invented certain new and useful Improvements in Receptacles for Photographs or the Like, of which the following is a description.

My invention belongs to that class of wall 10 ornaments particularly adapted for use as a receptacle for photographs and similar articles.

The object is to produce a simple and more 15 convenient device for the purpose stated which shall more effectually protect the photographs from dust and injury, while at the same time it is highly ornamental.

To this end my invention consists in the 20 novel construction, arrangement, and combination of parts herein shown and described, and more particularly pointed out in the claim.

In the drawings, wherein like reference characters indicate like or corresponding parts, 25 Figure 1 is a front elevation of my invention. Fig. 2 is a transverse section in line 4-4 of Fig. 1. Fig. 3 is a longitudinal section in line 3-3 of Fig. 1, and Fig. 4 is a side elevation of one of the ornamental candelabra adapted for 30 use with my device.

In the drawings, 1 represents the base or body of my device, provided with a flat back to hang snugly against the wall and also provided with side and end walls 2, 3, forming 35 a receptacle preferably rectangular in form. It is rectangular in cross-section and provided on its extension with brackets 4, 4, adapted to receive and support ornamental candelabra 5 or equivalent parts. The space inclosed be- 40 tween the side and end walls is provided with a plurality of transversely-extending pockets 6, 6, each having a front wall 7, thus forming a plurality of transverse receptacles substantially rectangular in form and adapted for the 45 convenient reception of photographs or similar articles, said receptacles extending the full width of said space, as shown in Fig. 2.

The whole base, as thus described, is highly ornamental, which effect is preferably enhanced by ornamental end scrolls 8, 8, secured 50 to the body and forming a part thereof. A door or cover 9 is hinged to the body 1, as at 10 10, the opposite edge and the body being provided with suitable coöperating engaging members 11, 12. The door 9 is formed to 55 swell outward, both transversely and longitudinally, forming a highly-ornamental panel 13, which may be embellished as desired. In practice the cover is of metal, suitably formed as described, upon the surface of 60 which any preferred portrait, painting, or other picture or ornamental production may be formed or prepared, and an outer surface of glass of suitable form preserves the same from harm and gives the whole a highly-ornamental finish. The inner surface of the door 9 is thus concave and is provided with one or more transverse pockets 14, 14, having 65 a straight inner face and a concave back. The pockets thus formed are deeper near the 70 center and taper outward toward the edges, as shown in Fig. 2. These pockets 14 are substantially of the full width of the door. It will thus be seen that the pockets 6, 6 are 75 adapted to contain photographs of substantially the same size, while the pockets 14, 14, are adapted to contain photographs of different sizes, the smaller ones being readily positioned in the center of the concave pockets 14, 14. 80

Where in the claims I refer to "rectangular pockets" I wish to be understood as meaning pockets substantially similar in form to the pockets 6, 6, while by "concave pockets" I mean pockets with one concave side 85 wall similar to the pockets 14, 14.

From the whole description it will be understood my device is highly ornamental and very useful. The body is substantially a candelabra-base, formed into a receptacle and 90 provided with an ornamental panel front, both the base and front being provided with transverse pockets or receptacles differing in form for the purpose stated.

Having thus described my invention, what I claim as new, and desire to secure by Letters Patent, is—

A device of the kind described, comprising 5 a body-piece forming a back, provided with a plurality of transverse rectangular pockets in which the fronts of said pockets are arranged parallel to the back of said body-piece, in combination with an oval cover pivotally 10 connected to the body and provided with a

plurality of transverse pockets each increasing in width toward the center of the cover and having a straight front and a curved back.

In testimony whereof I have hereunto signed my name in the presence of two subscribing 15 witnesses.

ISIDOR KELLNER.
